US0D1074961S

(12) **United States Design Patent** (10) Patent No.: **US D1,074,961 S**
(45) Date of Patent: ** May 13, 2025

(54) **HUMIDIFYING AIR PURIFIER**

(71) Applicant: **LG Electronics Inc.**, Seoul (KR)

(72) Inventors: **Hyewon Kim**, Seoul (KR); **Sehwan Bae**, Seoul (KR); **Seungho Baek**, Seoul (KR); **Ilha Park**, Seoul (KR); **Taewoo Yoo**, Seoul (KR); **Haein Jung**, Seoul (KR); **Hosik Jang**, Seoul (KR); **Soonho Jung**, Seoul (KR)

(73) Assignee: **LG ELECTRONICS INC.**, Seoul (KR)

(**) Term: **15 Years**

(21) Appl. No.: **35/520,327**

(22) Filed: **Mar. 16, 2023**

(80) **Hague Agreement Data**

Int. Filing Date: **Mar. 16, 2023**

Int. Reg. No.: **DM/229304**

Int. Reg. Date: **Mar. 16, 2023**

Int. Reg. Pub. Date: **Mar. 22, 2024**

(57)

CLAIM

The ornamental design for a humidifying air purifier as shown and described.

DESCRIPTION

1. Humidifying air purifier

1.1 : Perspective

1.2 : Front

1.3 : Back

1.4 : Left

1.5 : Top

1.6 : Bottom

(Continued)

Reproduction 1.4 is a left view where the right view is a mirror image.

1 Claim, 6 Drawing Sheets
